UNITED STATES PATENT OFFICE.

LEWIS H. McCULLOUGH, OF RICHMOND, INDIANA.

NON-INTERFERING FIRE AND POLICE TELEGRAPH SYSTEM.

SPECIFICATION forming part of Letters Patent No. 329,189, dated October 27, 1885.

Application filed April 1, 1885. Serial No. 160,938. (No model.)

To all whom it may concern:

Be it known that I, LEWIS H. McCULLOUGH, a citizen of the United States, residing at Richmond, in the county of Wayne and State of Indiana, have invented certain new and useful Improvements in Non-Interfering Fire and Police Telegraph Systems; and I do hereby declare the following to be a full, clear, and exact description of the invention, such as will enable others skilled in the art to which it appertains to make and use the same.

In an application for Letters Patent filed by me on the 5th day of August, 1884, I describe an arrangement of circuits for fire-alarm telegraph systems and a central-office apparatus by means of which it is made impossible to send in two alarms of fire at the same time, and thereby produce a false or confused signal. In another application filed on the same date I show and describe an improved multiple signal-box which is provided with circuit-controllers for sending at will either fire-alarm signals or signals for police, police-patrols, &c.

The invention described in my present application is in some sense a combination of my two former inventions; and it consists of a system of circuits and apparatus whereby the operation of either circuit-controller in my multiple signal-box or of both of them simultaneously will actuate separate receiving apparatus without interference, and whereby absolute non-interference is also secured with regard to signals of the same class in whatever order the circuit-controllers are operated. In the case of signals of the same class—as fire alarm signals—if two or more are rung in at the same time or in immediate succession, all but one will be shut out until that one is received. In the case of signals of different kinds—as fire and police or fire and police-patrol signals—if two are rung in simultaneously or successively, both will be received without confusion or mistake.

Prior to the invention of my non-interfering system of fire-telegraphs above referred to there was, so far as I know, no system in the operation of which interference between signals was not liable to occur. Besides obviating that danger, my present system, as already indicated, provides for sending over circuits in part the same fire-alarm and police or po-

lice-patrol signals by such means that the signals of either class not only do not interfere with each other, but are also free from liability to interfere with those of a class not their own.

In my non-interfering fire-telegraph system above referred to I run a wire from one pole of a battery in a loop back to the same pole, and I lead another wire from the opposite pole through gong and bell magnets in engine-houses and bell-towers, and arrange a number of open-circuit signal-boxes in multiple-arc relation between these wires. I also provide apparatus at a central station adapted to be actuated by the operation of any signal-box in such a manner as to cut every other signal-box out of the circuit. The central-office apparatus, besides cutting out all the boxes except the one first operated, causes a hand to point to the number of that box. I prefer on this account to call the central-office apparatus an "indicating apparatus" or "indicator."

In my present system I have precisely the same arrangement of circuits, gong and bell magnets, signal-boxes, and indicating apparatus; but I have, in addition to this, a similar system for police telegraphy, with a separate battery, loop, and receiving apparatus, but with the same return-circuits. The only extra wire that is required for the combined fire and police telegraph besides the loop is that necessary for connecting the indicators in the fire and police headquarters.

In the drawings which illustrate my invention and form a part of this specification, Figure 1 represents my system as a whole; and Fig. 2 shows a portion of a signal-box, together with the electrical connections within the same.

Referring to the drawings by letter, W is the battery for operating the fire-telegraph system, and X is the loop which runs out from and back to the same pole of the battery. Z' is the wire that leads from the opposite pole of the battery, and it passes, as shown, through engine-houses and bell-towers, as Y and R, which are provided with suitable receiving apparatus, as V. From the engine-houses and bell-towers it passes to the hand B of the central-office apparatus, which is mounted on a suitable frame. The hand B is normally held

from rotating in the direction of the arrow by a conducting-stop, d , which is attached to the armature of the magnet E in such a manner as to be normally held out in the path of the hand when the said magnet is not energized. The circuit passes from the stop d through the magnet E to a point, r , where it divides and goes through all the magnets F to the different signal-boxes, as will be fully explained hereinafter. The magnets F and E are arranged behind a dial-face similar to the one shown at A in the left of the drawings. This dial is provided with a series of slots, a , each of which is substantially at right angles to that radius of the dial which passes through its center. The armatures H of the magnets F have extensions k , which project into the slots a , and normally lie therein with their ends flush, or nearly so, with the dial-face. Whenever any magnet F is energized, it thrusts forward the extension k of its armature into the path of the hand B . The extension k of every armature is normally pressed by a spring, h , into that end of its slot a which is first reached by the hand B in its rotation. In pressing the extension k into that end of the slot the spring h also presses it against the platinum point n on the conducting-arm m , which is attached to the frame of the dial.

Tracing the circuit, now, from that pole of the battery to which it is connected, it passes through X in two directions, and by wires t to one terminal, c , of a circuit-closer in every signal-box. (See Fig. 2.) From the other terminal, c' , the circuit continues by wires 1 to binding-posts p ; by wires 2 to insulated plates o and their connecting-plugs; by wires 4 to extensions k , to platinum points n , to conducting-arms m ; by wires 5 to magnets F ; by wires 6 to common point r ; by wire 7 to releasing-magnet E ; by wire 8 to conducting-stop d , to hand or pointer B , and by wire Z' through the gong and bell magnets to the opposite pole of the battery.

It will be observed that the magnet E is common to all the box-circuits, while the magnets F are each in the circuit of a different box. On the operation of any signal-box, then, the magnet E will always be energized; but only that magnet F will be energized which is connected to the particular box that is operated. Suppose, for example, that the circuit-closer of box 23 is set in operation. At the first closure of the circuit the magnet E will withdraw the stop or detent d and release the hand or pointer B , and the magnet F , which is connected with box 23, will cause its extension k to project into the path of the hand and stop its rotation. At the same time the first stroke of 23 will be made on the gongs and bells. Now, the driving-spring (not shown) of the hand B is made considerably stronger than the springs h , in consequence whereof the extension k will be pushed away from the platinum n to the opposite end of the slot a , thereby breaking the circuit of all the box-magnets. The circuit of magnet E is broken

when the hand leaves the stop d . After the hand has reached the extension k , connected with box 23, and pushed it away from the point n , there is no circuit for any other box,

whereas that box will have a complete circuit through the gong and bell magnets whenever its own circuit-closer acts. Thus all the strokes of 23, except the first, will be sounded through a circuit which passes directly from one of the extensions k , through the hand B , and back to battery by the course already described.

It is understood, of course, that the fire-alarm circuit-closer in each box is adapted to close the circuit a definite number of times corresponding to the number of the box.

The tension of the driving-spring is made such that the hand B will be carried to the extension k farthest around the dial before the second closure of the circuit at the box.

As has been fully set forth in the application for Letters Patent above referred to, this system of fire telegraphy is absolutely non-interfering. Both the original and the secondary circuits traverse the hand B . As soon, therefore, as the hand has left the stop d , there is no circuit for any box except one that has already been operated. Moreover, in case two boxes should be operated at the same time, the hand would be mechanically obstructed from passing to the extension k which was farthest around the dial until the nearest extension k had been pushed back after the receipt of its box-signal. The extension k will be held in its forward position by the force of the spring h , pushing it against the end of the hand B . After the signal has been sent in, the extension k will be restored by hand or by automatic mechanism, as desired.

The plates o are ordinary metallic insulated plates attached to a board or frame at a central office, which board or frame also supports the dial and its connected apparatus. There are as many binding-posts p and as many magnets F as there are signal-boxes in the system, and the number of signal-boxes will usually correspond to the number of slots in the dial, less one, although the dial may be constructed to have several more slots than there are signal-boxes to provide for future needs or contingencies. For the sake of the clearness of the drawings, only eight box-magnets and eight binding-posts p are shown, although the number of slots in the dial at the left is represented as somewhat greater than that.

The signal-boxes are placed, as usual, in different parts of a city or village, and each connected with one of the magnets F and with the magnet E . The magnets F and E being operated simultaneously, the end of extension k will always be out in position to engage the hand B as soon as it comes along.

It will be seen that the signal-boxes 17, 21, &c., are each connected in two directions with one pole of the battery—a feature by virtue of which no box is cut out unless the circuit is broken on both sides thereof. If preferred,

a loop may be run from each binding-post *p* to a separate box, whereby each box will have double connections with each battery-pole. An accidental closure of the circuit, as by the 5 falling of a loose wire across both *X* and *Z*, or by the contact of both those wires simultaneously with telephone or telegraph wires or other grounded conductors, will sound one stroke on the gongs and bells, and cause the 10 hand *B* to point to that number on the dial-face which corresponds to the number of the precinct where the disturbance has taken place. The point of disturbance having been once located, it will not be difficult either by 15 night or day to take proper measures for removing its cause.

This constitutes substantially the invention which is covered by my application first mentioned.

20 Besides this invention, the drawings illustrate a non-interfering police-telegraph system, the operation of which is precisely the same, although it is provided with a different generator and different receiving apparatus. For 25 convenience, I shall call the wires *Z* the "return-circuits" of the boxes. Starting, now, from one pole of the battery *W*, I lead a loop, *X'*, as before, in a circuit back to the same pole, and from the opposite pole I lead a wire, 30 *Z'*, through a tap-bell magnet, *v*, to the hand of the dial located at the police-headquarters. The connections behind the dial are exactly the same as those illustrated at the right of the drawings, wires being run in the same 35 manner from the extensions *k* to the plates *o o*. From here the circuit goes back to the loop *X'* by way of the wires *3'*, binding-posts *P*, and wires *2'* to the corresponding wires, *2*, and from there to the signal-boxes over the routes 40 already described. Within the signal-boxes the connections are as shown in Fig. 2—that is, (for the police-telegraph,) by wire *Z* to the wheel-terminal *e'*, and by spring-terminal *e* and wire *t'* to the binding-post *f*. This binding-post is connected by wire *t* to the loop *X'*.

45 It will be seen that the return-circuits for the fire and the police telegraphs are for the most part identical. They do not begin to diverge until the central office of the fire-telegraph system is reached, and as this is nearly always in close proximity to the police-headquarters, where the other apparatus is located, it is evident that very little more wire is required for operating my non-interfering fire 50 and police telegraphs than would be required for either alone.

The police-telegraph system, being constructed on precisely the same principles as the fire-alarm-telegraph system already described, will be, like that, absolutely non-interfering. It remains to note that the two systems do not interfere with each other. Suppose, for example, that both circuit-closers in box 23 should be operated at the same time. 55 The outgoing circuit for the fire-telegraph system would be through either branch of the loop *X* and the wire *t*. The outgoing circuit

for the police-telegraph system would be through either branch of the loop *X'* and the wires *t'* and *t*. The return-circuit for both 70 systems would be the wire *Z* as far as the binding-post *p*, but would divide a little beyond that point, the current from battery *W* passing on through the magnets *F* and *E* of the fire-alarm indicator, and serving to operate the gongs and bells, as above described, and the current from battery *W'* passing similarly through the apparatus in the police-headquarters and sounding a definite alarm on the tap-bell *v*. 75

80 It is clear that the battery *W* cannot operate the police-alarm signal, as it can find no return through the police-office indicator. Similarly, the battery *W'* cannot operate the fire-alarm apparatus. For my police-alarm 85 signal-wheel I have shown a wheel having circuit-closing teeth arranged in three groups of two. In practice I shall have two or more wheels, differently toothed, on the same shaft, and shall provide means for moving either 90 wheel into line with the spring-terminal *e*. Signals corresponding to the number of the teeth are sounded on the tap-bell *v*, while the hand *B* points to the number of the box from which the signal is sent in.

95 Both the signal-wheels *c'* and *e'* are connected to the return-wire *Z*. The spring-terminals *c* and *e* are connected to the different loops, *X* and *X'*.

Having now described my invention, what I 100 claim, and desire to secure by Letters Patent, is—

1. The combination, with two generators, each having a conductor running in a circuit from one of its poles back to the same pole, 105 of two or more circuit-closers in multiple-arc relation between each of the said conductors and the opposite pole of the corresponding generator, the return-circuits being for the most part common, but dividing at some convenient point or points, and passing to the respective generators through separate receiving apparatus, substantially as set forth.

2. The combination, with two batteries, one designed to operate a system for sending 115 one class of signals and the other a system for sending another class of signals, and each having a conductor running in a circuit from one of its poles back to the same pole, of two or more circuit-closers, each representing its 120 own class of signals in multiple-arc relation between each of the said conductors and the opposite pole of the corresponding battery, the return-circuits being for the most part common, but dividing at some convenient point 125 or points, and passing to the respective batteries through separate receiving apparatus, substantially as set forth.

In testimony whereof I have affixed my signature in presence of two witnesses.

LEWIS H. McCULLOUGH.
